(57) **CLAIM**

The ornamental design for a raincoat for dogs, as shown and described.

DESCRIPTION

FIG. 1 is a top view of the raincoat for dogs of our new design in the open position;

FIG. 2 is a top view like FIG. 1 of the raincoat for dogs in the closed position and with the securing strap wrapped around the outer surface thereof;

FIG. 3 is a left side view thereof;

FIG. 4 is a right side view thereof;

FIG. 5 is a perspective view showing the top and rear thereof;

FIG. 6 is a bottom plan view thereof, with the securing strap unfastened; and,

FIG. 7 is a bottom view like FIG. 6, with a securing flap facing outward and in the open position to expose the interior of the raincoat for dogs.

1 Claim, 6 Drawing Sheets
